UNITED STATES PATENT OFFICE

LUCILLE MARTIE BITGOOD, OF NEW LONDON, CONNECTICUT, ASSIGNOR TO THE GOOD-
YEAR'S INDIA RUBBER GLOVE MANUFACTURING COMPANY, OF NAUGATUCK, CON-NECTICUT, A CORPORATION OF CONNECTICUT

DESIGN FOR A GAITER OR SIMILAR WATERPROOF RUBBER FOOTWEAR

Application filed May 9, 1931. Serial No. 39,790. Term of patent 3½ years.

To all whom it may concern:

Be it known that I, LUCILLE MARTIE BITGOOD, a citizen of the United States, residing at New London, county of New London, and State of Connecticut, have invented a new, original, and ornamental Design for Gaiters or Similar Waterproof Rubber Footwear, of which the following is a specification, reference being had to the accompanying drawings, forming part thereof, wherein:

Fig. 1 is a front perspective view of a gaiter or similar waterproof rubber footwear showing my new design; and

Fig. 2 is a front perspective view of the opposite side of the gaiter shown in Fig. 1.

I claim:

The ornamental design for a gaiter or similar waterproof rubber footwear, as shown.

Signed at New York, in the county of New York, and State of New York, this 29th day of April, 1931.

LUCILLE MARTIE BITGOOD.
